UNITED STATES PATENT OFFICE.

PAUL WILHELM SIEURIN, OF GOTTERBORG, SWEDEN.

LASHING DEVICE FOR LIFEBOATS.

1,333,739.

Specification of Letters Patent. Patented Mar. 16, 1920.

Application filed April 24, 1919. Serial No. 292,453.

To all whom it may concern:

Be it known that I, PAUL WILHELM SIEURIN, a subject of the King of Sweden, and a resident of Gottenborg, Sweden, have 5 invented certain new and useful Improvements in Lashing Devices for Lifeboats, of which the following is a specification.

The present invention relates to a device by means of which lifeboats swung out from 10 a ship's side are held securely lashed to ordinary swinging davits, whereby the life saving arrangements on board the vessel are considerably improved. With the hitherto known devices many difficulties and drawbacks 15 arise owing to the complicated arrangements for keeping the boats in their davits in a steady position while the ship is moving in a high sea. The said drawbacks are obviated by the present invention, where- 20 by considerable advantages are attained.

The invention is illustrated in the accompanying drawing in which Figure 1 is a side elevational view, and Fig. 2 a plan view thereof.

25 1 and 2 designate two ordinary davits and 3 a lifeboat which by means of tackle is suspended from them. From one of the davits, for example 1, projects a fixed arm 4, provided with a block 5, while the other 30 davit 2 at a suitable height over the deck is furnished with a block 6. Near the foot of the davit 2 there are two guide blocks 7 and 8 for each of two flexible lines 9 and 10 of steel or other suitable material, which lines, 35 as indicated in the drawing run through the blocks 5 and 6, and by means of a common fitting 13 on the inner gunwale of the lifeboat are joined to a line 11 led over and under the lifeboat 3, which line afterward 40 passes through a fitting 12 near the edge of the deck, from which it is attached to some easily accessible place of attachment. The lines 9 and 10 pass each to their line drum, which by a suitable gearing device is able 45 with great force to draw the respective lines taut. The fitting 13 is so connected with the inner gunwale of the lifeboat 3 that it is prevented from being detached from the boat in any other way than by being lifted out of 50 its position.

With a device in accordance with the above description the following advantages are attained: If the line 11 is secured on board and the lines 9 and 10 are drawn taut 55 by their line drums, which are suitably locked automatically, for example by pawls,

the boat is prevented in an absolutely effective way from moving in any direction, besides which the davits themselves are perfectly steady, because the line 9 passes 60 through the block 5 on the arm 4 from the davit 1.

When the lifeboat is hoisted to its highest position while the davits and the lines 9, 10 and 11 are drawn taut, all need of further 65 lashings, as well as of ordinary lashing booms is done away with. With the above described device it is also possible easily and rapidly to effect the swinging-out of the life-boat from its in-board position, which is of 70 great importance when the vessel has a "list."

Claims:

1. A lashing device for life boats, comprising a pair of davits, an arm projecting from one davit, a line guide carried at the 75 outer end of said arm, a line guide carried by the other davit, a line passing over and under the life boat, and a second line adapted to be drawn taut connected to the first mentioned line and passing over said line guides. 80

2. A lashing device for life boats, comprising a pair of davits secured to the ship's deck, an arm projecting from one of the davits near the foot thereof, a line guide carried at the outer end of said arm, a line guide 85 carried by the other davit in a higher plane than the first named line guide, a line adapted to be drawn taut over said line guides, and a second line passing over and under the lifeboat and to which the first 90 named line is connected.

3. A lashing device for life boats, comprising a pair of davits, an arm projecting from one davit, a line guide carried at the 95 outer end of said arm, a line guide carried by the other davit, a line passing over and under the life boat, a second line adapted to be drawn taut connected to the first mentioned line and passing over said line guides, and a pair of juxtaposed line guides between 100 which said second line passes.

4. A lashing device for life boats, comprising a pair of davits, an arm projecting from one davit, a line guide carried at the outer end of said arm, a line guide carried by the other davit, a line passing over and under said life boat, a second line adapted to be drawn taut and passing over said line guides, and means at the inner gunwale of 105 said life boat to which both of said lines are 110 connected.

5. A lashing device for life boats, com-

prising a pair of davits, an arm projecting from one davit, a line guide carried at the outer end of said arm, a line guide carried by the other davit, a line passing over and under said life boat, a second line adapted to be drawn taut and passing over said line guides, means at the inner gunwale of said life boat to which both of said lines are connected, and means beyond the life boat

through which the free end of the line passing about the life boat extends. 10

In testimony whereof I have signed my name to this specification in the presence of two subscribing witnesses.

PAUL WILHELM SIEURIN.
